UNITED STATES PATENT OFFICE.

CHARLES CAILLE, OF LE PERREUX, FRANCE.

APPARATUS FOR THE UTILIZATION IN A REHEATER OF THE EXHAUST-STEAM OF LOCOMOTIVES.

No. 852,868.

Specification of Letters Patent.

Patented May 7, 1907.

Application filed October 1, 1906. Serial No. 336,958.

To all whom it may concern:

Be it known that I, CHARLES CAILLE, a citizen of the Republic of France, residing at 7 Rue des Vignes, Le Perreux, in the Republic of France, have invented new and useful Improvements in Apparatus for the Utilization in a Reheater of the Exhaust-Steam of Locomotives, of which the following is a specification.

10 The present invention has for its object an apparatus which permits of the utilization in a re-heater of a portion of the exhaust steam in locomotives, which now is employed only in drawing air through the furnace.

15 A form of construction of the invention is represented in sectional elevation on the accompanying drawing.

The invention consists in principle of a re-heater interposed in the exhaust passage and 20 forming a closed vessel through which a portion of the escaping steam is diverted, after emerging from the exhaust chest before reaching the draft producing escape throat.

25 In practice, in the exhaust passage below the throttle-valves *b* of variable opening is interposed an ejector of which the central cone *c* is connected by a pipe *d*, to the exhaust-chest *e* of the cylinders, and to this pipe is branched one extremity of a pipe *f* by which 30 is diverted a portion of the exhaust steam, the other extremity being joined to the utilizing apparatus, that is to say to a tubular re-heater *k*.

The surrounding cone *g* of the ejector is 35 connected by a pipe *h* to the outlet *i* of the vapor of the re-heater. The re-heater, which may be variously constructed, comprises a chamber *m* for the admission of steam, closed by a tube plate *o*, carrying one of the extremities of a series of tubes *n* the opposite extremities of which are secured to a tube-plate *q* and open into a chamber *p* for the outlet of 40 the steam and water of condensation.

Within the casing *k* between the tube plates *o* *q*, and around the tubes *n*, is produced a circulation of water in the inverse direction of the circulation of the steam, *r* being the admission pipe of the cold water, and *s* the outlet pipe of the re-heated water. This 45 arrangement can be inverted, in respect that the water may be within the tubes and the steam around them. The re-heater is completed by a small pipe *t* for the evacuation of the water of condensation, to which may be

united an automatic steam-trap of dilatation or other form.

A portion of the exhaust steam which escapes from the chest *e*, by the pipe *d*, is diverted to the pipe *f*, through an orifice *u*, regulated by a register or a flap *v*, the vapors not diverted escape by the central cone *c* of the ejector, and draw into the cone *g* by the pipe *h*, the residuary vapors leaving the re-heater at *i*. This suction of the residuary vapors produces an active circulation on one of the 55 walls of the cluster of pipes *n*, over the other wall of which sweeps the stream of water with inverted circulation. The result being that the walls of transmission for the heat are maintained constantly active and the 60 condensed water being carried toward the steam-trap, not only is thus utilized, as rapidly and as perfectly as possible, the heat derived by the exhaust steam, but also the 65 steam which has not been used in the re-heater is recovered. The diversion effected 70 on the exhaust steam does not cause any appreciable diminution of the forced draft in the furnace, for the interposed ejector assures the preservation of the moving force of 75 the stream toward the contracted throat at *b*.

The re-heater constitutes in fact a closed vessel interposed as a by-path to the exhaust passage. In this will not be found the conditions of an ordinary re-heater which renders possible the re-entry of air and the consumption without possible recovery of all the 80 vapor diverted.

It goes without saying that the interposed ejector can be connected with the exhaust 90 pipes from the two steam cylinders, or it will be possible, if so desired, to provide an interposed ejector for each of the engines, the re-heater being supplied by steam from one or both exhausts as may be desired.

95 I claim:

1. In combination with the steam chest and the exhaust passage therefrom having the nozzle therein, of a re-heater having its inlet connected to the exhaust passage below the nozzle and its outlet connected to that part of the exhaust passage surrounding the outlet end of the nozzle.

2. In combination with the steam chest and the exhaust passage therefrom having an 105 ejector therein of a re-heater having its inlet and outlet ports connected to the interior and exterior parts of the ejector.

3. In combination with the steam chest and the exhaust passage therefrom having an ejector therein of a re-heater having its inlet and outlet ports connected to the interior and exterior parts of the ejector, and a flap in the exhaust passage controlling the inlet of the re-heater.

In testimony whereof I have signed my name to this specification in the presence of two subscribing witnesses.

CHARLES CAILLE.
